G. HEIL

AERIAL AND LIKE POST

Filed March 21, 1922

FIG.1.

FIG. 2.

Inventor.
Georg Heil.
Attorney. R. Manday

UNITED STATES PATENT OFFICE.

GEORG HEIL, OF LAHR, BADEN, GERMANY, ASSIGNOR TO GEBR. HIMMELSBACH AKTIENGESELLSCHAFT, OF FREIBURG, BADEN, GERMANY.

AERIAL AND LIKE POST.

Application filed March 21, 1922. Serial No. 545,622.

To all whom it may concern:

Be it known that I, GEORG HEIL, of Lahr, Baden, Germany, a citizen of the German Republic, have invented certain new and useful Improvements in Aerial and like Posts, of which the following is a specification.

This invention relates to aerial and like posts, more particularly for supporting high tension and low tension electric wires. Its object is to effect an improvement in the construction of what may be called twin or double posts, that is to say posts of the kind in which two vertical timbers are coupled with each other to make a single post. The posts have the advantage, over plain one-piece posts, of greater rigidity, and of offering less surface to wind sweeping along the line. Moreover, they are more durable for the reason that the thinner timbers used can be more efficiently impregnated with preservation substances. On the other hand certain difficulties have heretofore been encountered in coupling together the two members forming the post. Where bolts are used, traversing both the members, holes of considerable size are necessary, and these substantially weaken the timber. Moreover, under the bending stresses to which the post is subjected, the bolts are deflected and bear against the fibres in the direction of the grain, so that in course of time holes become enlarged and assume an elliptical shape. The bolts thus become loose and allow of relative movement of the two coupled members. The protruding heads and nuts of the bolts are liable to cause inconvenience and injury when the post is climbed. Similar difficulties occur when the members are coupled by means of ties and dowel pins, which also weaken the timber and are more costly in time and labour.

According to my invention these disadvantages are removed by using a flanged coupling plate placed between the two members of the twin post, and screwing or bolting the flanges to the said members.

A construction embodying this arrangement is shown by way of example in the accompanying drawings, in which:—

Fig. 1, is an elevation of a portion of the twin post with the coupling, and

Fig. 2 a cross section thereof.

In the drawing, *a* and *b* designate the two members of the twin post, *c* is a composite coupling plate, and *d*, *d* are screws whereby the flanges are fixed to the timbers.

The coupling plate shown is formed of two symmetrical parts, each having a web and two curved flanges, and the two webs are riveted to each other. The flanges partly embrace the members *a* and *b* but are confined to the space between the post members, that is to say between parallel tangents common to both members *a* and *b*. The screws *d* are oblique to these tangents and to the vertical plane containing the axes of the members *a* and *b*, so that bending stresses force the screws against the grain of the wood, and the tendency of the screws to enlarge their holes is thus greatly reduced.

There may be any desired number of coupling plates between the two post members.

What I claim as my invention and desire to secure by Letters Patent of the United States is:—

1. In a twin aerial or like post, the combination of two parallel post members, a flanged coupling plate having a web between said post members and having flanges abutting against said members, and screws fixing said flanges to the post members against which they abut respectively, said screws being oblique to the plane containing the axes of the two post members.

2. In a twin aerial or like post the combination of two parallel post members, a flanged coupling plate having a web between said post members and having flanges abutting against said members, and screws fixing said flanges to the post members against which they abut respectively, said screws being oblique to the plane containing the axes of the two post members, and said flanged coupling plate being confined to the space between two parallel planes tangential to both the post members.

In witness whereof I have signed this specification in the presence of two witnesses.

GEORG HEIL.
